UNITED STATES PATENT OFFICE

172,568

HANGER FOR HATS, TIES, AND THE LIKE

Bonnie M. Stahl, Denver, Colo.

Application July 10, 1953, Serial No. 25,881

Term of patent 14 years

(Cl. D33—8)

To all whom it may concern:

Be it known that I, Bonnie M. Stahl, a citizen of the United States, residing at the city and county of Denver and State of Colorado, have invented a new, original, and ornamental Design for a Hanger for Hats, Ties, and the like, of which the following is a specification, reference being had to the accompanying drawing, forming a part hereof.

Fig. 1 is a perspective view of a hanger for hats, ties, and the like, showing my new design, the top left hat-holding ring being shown folded, while the remaining rings are extended.

Fig. 2 is a side elevational view thereof, with the top two rings being folded while the remaining ones are extended.

I claim:

The ornamental design for a hanger for hats, ties, and the like, as shown and described.
